(57) **CLAIM**

The ornamental design for an air conditioner as shown and described.

DESCRIPTION

FIG. 1 is a top, front and right side perspective view of an air conditioner according to our new design;

FIG. 2 is a bottom, front and right side perspective view of the air conditioner of FIG. 1.

FIG. 3 is a front elevational view of the air conditioner of FIG. 1

FIG. 4 is a rear elevational view of the air conditioner of FIG. 1;

FIG. 5 is a left side view of the air conditioner of FIG. 1;

FIG. 6 is a right side view of the air conditioner of FIG. 1;

FIG. 7 is a top plan view of the air conditioner of FIG. 1; and,

FIG. 8 is a bottom plan view of the air conditioner of FIG. 1.

The broken lines depict portions of the air conditioner that form no part of the claimed design.

1 Claim, 8 Drawing Sheets
